UNITED STATES PATENT OFFICE

2,531,538

AIR CONTROL UNIT FOR OIL BURNERS

Cecil W. Smith, Waterman, Ill.

Application May 6, 1948, Serial No. 25,403

5 Claims. (Cl. 158—76)

1

This invention relates generally to domestic oil burners and in particular to an air control unit adapted to be positioned within an air supply tube, and about a fuel nozzle in the tube, to vary the pattern or shape of the burner flame and the action of the air within the flame.

The control of combustion air and the mixing of such air with fuel in an oil burner is an important factor in the heating efficiency of a burner, particularly oil burners of domestic type. About fourteen pounds (183 cubic feet) of air is required to burn one pound of fuel oil. The amount of air above that actually required to burn the oil is generally referred to as excess air. Since any excess air is heated to the same temperature as the products of combustion, the excess air carried up a flue or chimney carries this heat with it. As a result all heat thus carried away by excess air is wasted and lost for heating purposes.

This loss of heat is also evidenced by the fact that excess air acts to cool the flame and the resultant products of combustion so that the flame is inefficient and results in the production of exhaust gases having a low carbon dioxide reading.

When an amount of air insufficient for actually burning the fuel is used, the flame is generally sooty and smoky, and coats the furnace and boiler heating surfaces so as to thermally insulate such parts. It has been estimated that a coating of soot an eighth of an inch thick, on the boiler heating surfaces, can cause an increase in the fuel consumption of the burner of as much as twenty-five per cent.

Because of the heat losses resulting from either excess air for burning, or insufficient air for burning, the air setting on an average domestic oil burner is adjusted so as to give the highest carbon dioxide reading possible without producing a smoky flame or fire. The percentage of carbon dioxide in the flue gases is generally recognized as an important factor in the combustion performance of a burner and the Federal Housing Administration requirements for a burner, to be financed by that agency, is that the burner shall be capable of producing and maintaining a carbon dioxide reading of not less than eight per cent. It will be appreciated that this reading is relatively low when based on a carbon dioxide reading of fifteen per cent which represents substantially perfect combustion with no excess air and no preventable fuel loss.

A further important factor in the efficient burning of fuel is the manner in which the fuel in the flame is acted upon by the combustion air. Thus many of the burners in commercial use

have a flame pattern of a generally flat conical shape with a spiral twist in it. A flame with a spiral twist tends to provide for a more intimate mixing of the fuel with the air for combustion and in turn for a more efficient burning of the fuel. In other words, where combustion air is supplied in what may be called a straight flow or stream, as contrasted to a whirling or spiral motion of the air in the air stream, the fuel and combustion air tend to travel in separate paths so that insufficient air mixes with the fuel for burning purposes.

However, when the spiral or whirling motion of the combustion air is excessive, the heavy ends of the fuel are thrown through the flame without being burned, rather than being suspended in the flame for intimate mixing and burning with the combustion air. Fuel thus thrown out of the flame is usually evidenced by an orange color in the flame and soot showings on the wall of the firebox, and boiler surfaces.

It is seen, therefore, that the volume of combustion air supplied to the flame, to reduce as far as possible the use of excess air, and the motion of the combustion air must both be given consideration in the obtaining of an overall efficient burning of the flame.

It is an object of this invention, therefore, to provide an improved air control unit for an oil burner.

30 A further object of this invention is to provide an air control unit for an oil burner, which is capable of being adjusted to change both the shape or pattern of the flame and the action or movement of the air in the flame.

35 Yet another object of this invention is to provide an air control unit for an oil burner of a construction such that the burner is capable of operating with substantially no excess air and with a carbon dioxide reading of fourteen per cent and higher.

40 A still further object of this invention is to provide an oil burner in which an air control unit is constructed and arranged relative to a fuel nozzle, such that a smooth flow of air is supplied to the flame whereby the flame burns evenly and without practically any galloping or pulsating action.

45 Another object of this invention is to provide an air control unit for an oil burner adapted to vary the pattern of the burner flame such that all of the fuel particles are substantially completely burned while in suspension within the flame.

50 55 A feature of this invention is found in the provision of a tubular air control unit for an oil

burner arranged within an air supply tube for adjustable movement longitudinally of the tube, and constructed so as to form three separate air supplies to the burner nozzle for combustion purposes. The nozzle is disposed in a central air passage, in which the air flows with a spiral motion. A pair of annular passages are concentrically arranged about the central passage, one of which has straight flowing air and the other spiral flowing air. The air in the central passage constitutes the main combustion air and is maintained at a substantially constant volume and velocity. The air in the two annular passages is supplementary air for combustion and, on adjustable movement of the air control unit, the air in the annular passages is relatively varied as to volume and velocity so as to produce a flame with pattern characteristics providing for a highly efficient burning of the fuel in the flame.

Yet another feature of this invention is found in the provision of an air control unit for the air supply tube of an oil burner, which is adjustable to vary the action of supplementary air for combustion on the main air for combustion to elongate or shorten the length of the burner flame, concurrently with varying the angle of twist or spiral in the flame to provide a flame with highly efficient burning characteristics.

Further objects, features and advantages of this invention will become apparent from the following description when taken in connection with the accompanying drawings, in which:

Fig. 1 is a perspective view of the front end portion of an air supply tube of an oil burner, showing the assembly therein of the air control unit of this invention, with certain parts being broken away to more clearly show such assembly;

Fig. 2 is a longitudinal sectional view taken on the line 2—2 of Fig. 1;

Fig. 3 is illustrated similarly to Fig. 2 and shows the air control unit in a changed position therefor;

Figs. 4 and 5 are transverse sectional views as seen along the lines 4—4 and 5—5, respectively, in Fig. 3; and

Fig. 6 is a diagrammatic showing of the flame pattern when the air control unit is in its adjusted position shown in Fig. 2.

With reference to the drawings, the air control unit of this invention, designated generally as 10, is shown in Figs. 1 and 2 in assembly relation within the front end of a cylindrical air supply tube 15 forming part of a domestic oil burner. The rear end 16 of the air supply tube is in suitable fluid connection with a source of combustion air such as a fan or the like (not shown). Mounted about the front end of the tube is a hood or skirt 17 provided with a contracted outlet 18 which has its defining wall or surface 19 tapered or inclined in a rearward and outward direction.

A fuel nozzle 21, centrally located within the front of the air supply tube 15 and to the rear of the outlet 18, has a rearwardly extended fuel supply tube 22 adapted to be connected with a source (not shown) of an air and fuel mixture. The nozzle 21 is equipped with usual electrodes 23 for initiating combustion of the mixture discharged from the nozzle.

The air control unit 10 comprises a pair of tubular members 24 and 26, arranged in a concentric relation, with the tubular member 26 within the tubular member 24. The outer tubular member 24, from its rear end 27, is formed in

succession with a straight cylindrical section 28, an inwardly and forwardly curved section 29, a forwardly and outwardly inclined section 31 and, finally, an inwardly and forwardly inclined front end section 32. It will be noted, for a purpose to appear later, that the front end section 32 and inclined section 31 are reversely inclined so that their junction 33 constitutes a circumferential peak about the outer tubular member 24.

10 The inner tubular member 26 is constructed in succession from its rear end 34, with a straight relatively short section 36, a forwardly and inwardly tapered or flared section 37, and a forwardly and outwardly tapered section 38.

15 Mounted about the front end of the tapered section 38 is a combination air deflector and air cushioning member 39 of an irregular shape, formed with a rear section 41 mounted about the front end of the tapered section 38 and secured thereto as by welding or the like. The section 41 terminates at its rear end in a laterally projected flange 42. Forwardly from its section 41, the combination member 39 has a laterally inwardly extended section 40 which terminates

20 in a front end section 43 which is inclined forwardly and inwardly. As best appears in Figs. 2 and 3, the front end sections 32 and 43 of the tubular members 24 and 26, respectively, are at an inclination corresponding substantially to the inclination of the side wall 19 of the outlet 18.

25 An air cushioning member 44 is arranged within the combination member 39 and is formed with a front end section 46 adapted to be secured to the inner side of the front end section 43 of the inner tubular member 26, and a straight rearwardly extended section 47 which is in a spaced relation with the front end of the tapered section 38 of the inner tubular member

30 26, so that an air pocket or chamber 48, open at its rear end, is formed between the tapered section 38, the straight section 47 at the rear end of the air cushioning member 44, and the intermediate section 40 of the combination member 39.

35 The straight rear section 36, of the inner tubular member 26, is adapted to fit against the inner peripheral surface of the straight section 28 of the outer tubular member 24, and is secured thereto as by welding. The tubular members 24

40 and 26 are thus assembled together in fixed relative positions, with the straight section 28 of the outer tubular member 24 extending rearwardly beyond the straight section 36 of the inner tubular member 26, and with the front end sections 32 and 43 terminating in substantially a common vertical plane at the forward end of the air control unit 10.

45 The unit 10, comprising the tubular members 24 and 26, is slidably supported for longitudinal movement within the air supply tube 15 by the provision of means including a series of longitudinally extended fins 51 (Figs. 2 and 4) spaced about the straight section 28 of the outer tubular member 24. By virtue of the fins 51, the air control unit 10 is supported in a concentrically spaced relation within the air supply tube 15.

50 Located rearwardly of the nozzle 21 is a nozzle supporting member 52, of a cylindrical shape, having a rear end 53 of a reduced section (Figs. 2 and 3). The nozzle supply line 22 and holders

55 54 for the electrodes 23 extend through the nozzle support 52. A series of inclined air deflecting vanes 56 are spaced about the front end of the nozzle support 52, which is adapted to be positioned within the straight rear end section

28 of the outer tubular member 24, such that the free or outer sides 56 of the vanes 50 are in slideable contact with the inner peripheral surface of such rear end section. With the nozzle support 52 thus positioned, the nozzle 21 is concentrically located within the inner tubular member 26.

It is seen, therefore, that the assembly of the air control unit 10 within the air supply tube 15 forms within the air supply tube a central air passage 57, defined by the inner tubular member 26 and the rear end 28 of the outer tubular member 24, an inner annular air passage 58 formed between the tubular members 24 and 26, and an outer annular passage 59 formed between the air supply tube 15 and the outer tubular member 24. From a consideration of Figs. 4 and 5, it is seen that the annular air passages 58 and 59 are concentrically arranged relative to the central air passage 57. Air to the inner annular passage 58 (Figs. 3 and 4) is supplied from the outer annular passage 59 through a series of circumferential holes 61 formed in the straight section 28 of the outer tubular member 24, at a position forwardly of the rear straight section 36 of the inner tubular member 26.

The vanes 50 (Figs. 2 and 4) on the nozzle support 52, provide for the movement of the air flow in the central passage 57 with a spiral or whirling motion. A straight flow of air takes place in the inner annular passage 58. The air flow in the outer annular passage 59 is substantially straight up to the openings 61 in the outer tubular member 24. A whirling or spiral motion is then imparted to the air by the provision of inclined vanes 63 spaced about the tapered section 31 of the outer tubular member 24. As a result spiral or whirling air is discharged from the central passage 57 and the outer annular passage 59, while a straight flow of air is discharged from the inner annular passage 58.

The air flow in the central passage 57 is the main combustion air and constitutes about thirty-five per cent of the total air flow in the air supply tube 15. The air flow in the annular passages 58 and 59 is the supplementary air for combustion and constitutes about sixty-five per cent of the total air flow in the air supply tube, which supplementary air is relatively varied between the annular passages 58 and 59 on adjustment of the air control unit 10 longitudinally of the air supply tube.

Adjustment of the control unit 10 is accomplished by means including a rod member 64 having its front end in looped engagement, as indicated at 66 (Figs. 2 and 4), with one of the fins 51 and which extends rearwardly through the air supply tube 15 such that its rear end (not shown) is accessible from the outside of the rear end of the air supply tube. Thus by merely a push and pull manipulation of the rod 64, the control unit 10 is adjustably moved forwardly and rearwardly within the air supply tube.

As previously explained, the front section 43 of the inner tubular member 26, and the front section 32 of the outer tubular member 24 are at an inclination corresponding substantially to the inclination of the outlet side wall 19. A foremost adjusted position of the air control unit 10 is defined by the contact of the front section 32 with the outlet wall 19, which parts are adapted for a substantially seated engagement, as shown in Fig. 3. Thus when the control unit is in its foremost position, no air is discharged from the outer annular passage 59.

In the adjustment of the air control unit, the fins 51 on the outer tubular member 24 are in slideable contact engagement with the air supply tube 15, while the outer or free sides 56 of the vanes 50, on the nozzle support 52, are in slideable contact with the inner peripheral surface of the straight section 28 of the outer tubular member 24. Stated otherwise, the air control unit, during adjustment, is moved relative to the air supply tube 15, the nozzle 21 and its support 52.

In the operation of the air control unit, assume the unit to be in its position shown in Fig. 2 at which the outer annular passage 59 is open to the outlet 18. As shown diagrammatically in Fig. 6, the whirling or spiral air from the outer annular passage 59 follows a path indicated by the spiral at 67. The whirling air discharged from the central air passage 57 through the outlet 18 follows a path indicated by the spiral at 68. The straight air from the inner annular passage 58 tends to converge forwardly of the outlet 18, as illustrated by the lines 69.

Without the straight air from the annular passage 58, the spiral air from the central passage 57 and the outer annular passage 59 would tend to spread outwardly from the outlet 18 to in turn reduce the pitch or distance between adjacent flights of the spirals. In other words, the flow of combustion air outwardly from the outlet 18, and in turn the shape and pattern of the resultant burner flame, would result in a relatively short flame having a sharp twist or spiral and a relatively large diameter. Such a high whirling motion of the combustion air acts to throw the fuel discharged from the nozzle 21 outwardly from the flame without completely burning the fuel.

By virtue of the straight air from the inner annular passage 58, tending to converge at a point forwardly of the outlet 18, the twist or spiral as well as the diameter of the spiral are decreased and the resultant flame is elongated. The fuel discharged from the nozzle 21 by virtue of the air from the passage 58 crossing the paths of the spiral air from the passages 57 and 59, is thus more intimately mingled with the combustion air and is retained in suspension within the flame for complete burning. A relative variation in the velocity and volume of the supplementary air discharged from the annular passages 58 and 59 is thus effective to concurrently vary the angle of twist in the flame, the diameter of the flame and the length of the flame.

A maximum elongation or axial projection of the flame from the outlet 18 is obtained on adjustment of the air control unit 10 to its foremost position shown in Fig. 3. At this position a maximum volume and velocity of straight air from the inner annular passage 58 acts only upon the spiral air from the central passage 57 in a manner such that this spiral air is substantially confined within the straight air discharged from the inner annular passage.

As the air control unit is moved rearwardly from its foremost position shown in Fig. 3, and toward its position shown in Fig. 2, the volume and velocity of straight air from the inner passage 58 is progressively decreased concurrently with a progressive increase in the volume and velocity of spiral air discharged from the outer annular passage 59. In turn, the flame pattern is progressively shortened along with an increase in its angular twist.

On adjustment of the air control unit 10, therefore, the flame pattern is capable of being varied over a relatively wide range of lengths and

corresponding angular twists so as to obtain a desired flame having a high burning efficiency. It will be noted further that the volume and velocity of the spiral air discharged from the central air passage 57 is substantially constant for all adjusted positions of the control unit 10, and that the air discharged from the annular passages 58 and 59 is relatively varied as to velocity and volume with each adjusted position of the air control unit.

In one embodiment of the invention the flame starts at a position of about one and one-half inches away from the outlet 18 and maintains substantially the same position for all adjusted positions of the air control unit 10.

It has been found that the heat from the flame is radiated to the hood or skirt 17 and then conducted to the vanes 63. The heat thus conducted to the vanes 63 is carried away by the air flow through the outer annular passage 59. Further, the heat from the flame is continuously carried away from the nozzle 21 by the action of the air flowing through the passages 57 and 58. As a result the nozzle 21 is always retained cool so that any clogging of its discharge orifice by fuel caking is substantially eliminated. The flame pattern, and in turn the burning efficiency of the flame, are thus capable of being maintained substantially constant over prolonged periods of burner operation.

The usual action of a fan or blower, now generally used in domestic oil burners for supplying combustion air, results in the air being moved with a pulsating or wave action. Unless this pulsating action is eliminated or substantially reduced, the flame tends to pulsate or gallop. The flame pattern is thus irregular and the variation in combustion air supplied to the flame acts to reduce the overall heating efficiency of the flame.

A pulsating or galloping action of the flame is substantially eliminated in the present invention by means including the combination member 39 and the air cushioning member 44. The inner tubular member 24 is formed with a series of circumferential openings 71 (Figs. 2 and 5) which are arranged rearwardly of the lateral flange 42 on the combination member 39. The flange 42 acts to cushion or choke the air passing through the inner annular passage 58 while the openings 71 provide for an equalizing of the velocity pressures of the air flowing through the central passage 57 and the inner annular passage 58. The resultant overall effect is the cushioning of the air in the inner annular passage 58 so that it flows evenly from such passage.

The spiral air in the central passage 57, by virtue of the action of centrifugal force, tends to travel about the inner peripheral surface of the inner tubular member 24. This air on moving into the cushioning chamber 48 is cushioned or choked so as to eliminate any pulsating action therein prior to its flow outwardly from the central passage 57. It is seen, therefore, that the air cushioning member 44 and the flange 42 are arranged substantially opposite each other on the inner tubular member 24 and, in conjunction with the equalizing action provided by the openings 71, provides for a smooth and even flow of the air through the passages 57 and 58. A cushioning action of the air passing through the outer annular passage 58 is accomplished by the choking action of the vanes 63 in conjunction with the openings 61. Also a choking effect of the air flowing through the central passage 57 is obtained by the nozzle support 52, it being un-

derstood that the air admitted into the passage 57 initially flows about the nozzle support for travel about the vanes 50.

As previously mentioned, the junction 33 between the sections 31 and 32 on the outer tubular member 24 constitutes a circumferential peak on such member. It is also seen (Figs. 2 and 3) that the nozzle is of an irregular shape and formed at its front end with reversely inclined sections 80 and 81 which form a circumferential peak at their junction 82.

In the stopping and starting of burner operation, drops of fuel tend to form at the discharge orifice 85 (Fig. 1) of the nozzle 21. In the present invention these drops flow downwardly on the nozzle section 80 to the peak 82, and then fall downwardly by the action of gravity into the inner tubular member 26. From the inner tubular member 26, the fuel drops flow through the openings 71 on to the inclined section 31 of the outer tubular member 24 and then through an opening 83 formed in the peak 33 at the lower side of the outer tubular member 24. From the opening 83 the fuel drops to the lower side of the air supply tube 15. The hood 17 is formed with an upwardly and rearwardly slanted opening 84, the rear end 86 of which is in substantial alignment with the lower side of the air supply tube 15. As a result any fuel drops accumulating on the nozzle 21 follow the above described path for passage into the burner fire box. This drainage of the fuel drops from the nozzle eliminates any accumulation of free fuel within the air supply tube.

From a consideration of the above description, it is seen that the invention provides an air control unit for an oil burner which is of a simple and compact construction, and capable of adjustment to obtain a flame pattern having a high burning efficiency. Air for combustion is supplied from three different sources, one of which remains constant as to the velocity and volume, and the other two of which are relatively variable as to velocity and volume in direct response to an adjustment of the control unit. The air from such three sources are combined at the outlet of the air supply tube for a complementary action on each other to produce a controlled air flow for mixing and intermingling with the fuel mixture supplied from the burner nozzle. By controlling the combustion air in accordance with this invention, flames of a substantially white color and with practically no smoke are consistently obtained. Further, carbon dioxide readings from the products of combustion of these flames as high as 14.2% have been obtained. Adjustment of the air control unit is predicated on achieving a white flame, and by virtue of the nozzle 21 being relatively cool at all times, and thus free from clogging, no further adjustment is required over a prolonged time period of burner operation.

Although the invention has been described and illustrated with respect to a preferred embodiment thereof, it is to be understood that it is not to be so limited since changes and modifications can be made therein which are within the full intended scope of this invention, as defined by the appended claims.

I claim:

1. In an oil burner, an air supply tube having a contracted outlet at its front end, a fuel nozzle within said air supply tube at the forward end thereof, a first tubular member movably supported in a spaced relation within said air supply tube for adjustable movement longitudinally of

said air supply tube, a second tubular member arranged in a spaced relation within said first tubular member for movement therewith, means for imparting a spiral motion to the air flowing through said second tubular member, other means for imparting a spiral motion to the air flowing in the space between said air supply tube and said first tubular member, means for admitting a portion of the air from said last mentioned space into the space between said first and second tubular members at all adjusted positions of said first and second tubular members, and means for moving said first and second tubular members to an adjusted position, with the forward ends of said two tubular members and the outlet of said air supply tube being relatively constructed and arranged such that the first tubular member is movable into a seated engagement with the air supply tube at said outlet to stop the flow of air between said first tubular member and said air supply tube.

2. In an oil burner, an air supply tube having an outlet at its forward end, a pair of tubular members arranged in a concentric relation within the forward end of said air supply tube so as to form a central air passage and a pair of annular passages about said central passage, a fuel nozzle in said central passage, means for imparting a spiral motion to the air flow in said central passage, other means for imparting a spiral motion to the air flow in the outer one of said annular passages, means for adjustable moving said pair of tubular members as a unit toward and away from said outlet, means for admitting air from said outer annular passages into said inner annular passage at all moved positions of said tubular members, and means for stopping the flow of air through said outer annular passage when said unit is moved to an extreme forwardly moved position therefor.

3. In an oil burner, an air supply tube having a contracted outlet adjacent its forward end, a first tubular member movably supported in a concentrically spaced relation within said air supply tube having its front end portion extended inwardly and forwardly, means for adjustably moving said first tubular member longitudinally of said air supply tube, with a forwardly moved position of said tubular member being defined by the seated engagement of its front end portion with said outlet, a second tubular member arranged in a concentrically spaced fixed relation within said first tubular member having a flared rear portion in contact engagement with the inner peripheral surface of said first tubular member, said first tubular member having a series of circumferential openings therein located forwardly of the rear end of said second tubular member, a nozzle supporting member arranged in a concentrically spaced relation within said first tubular member at a position rearwardly of said second tubular member, a fuel nozzle within said second tubular member having a fuel supply portion carried in said supporting member, means for imparting a spiral motion to the air flowing in the annular space between said air supply tube and said first tubular member, other means for imparting a spiral motion to the air flowing through said second tubular member, and means for moving said first and second tubular members as a unit toward and away from said outlet to provide for a relative variation in the flow of air through said annular space and said second tubular member.

4. In an oil burner, an air supply tube having an inwardly and forwardly tapered outlet in its front end, an air control unit movably supported within the front end of said air supply tube for adjustable movement longitudinally of said air supply tube, said air control unit being constructed to form within said air supply tube a central air passage and a pair of annular air passages concentrically arranged about said central air passage, a fuel nozzle within said central air passage, means at the front end of said air control unit adapted to engage the tapered portion of said outlet at a forwardly adjusted position of said air control unit to stop the flow of air through the outer one of said pair of annular passages, means providing for the admission of air from said outer annular passage into the inner annular passage of said pair of air passages at all adjusted positions of said air control unit whereby to relatively vary the volume flow of air through said two passages in response to an adjustment of said control unit, and means for imparting a spiral motion to the air flowing through said central passage and the outer one of said annular passages.
5. In an oil burner, an air supply tube having a contracted outlet at its front end, a nozzle within said air supply tube adjacent the front end thereof, a pair of tubular members arranged in a concentrically spaced relation over their forward sections and with the rear section of the inner tubular member being of a flared construction and secured to the inner peripheral surface of the outer tubular member, with the outer tubular member having a series of circumferential openings therein located forwardly of the rear end of said inner tubular member, means supporting said outer tubular member in a concentrically spaced relation within the front end of said air tube so that said nozzle is within said inner tubular member, with the front ends of said tubular members being inclined inwardly and forwardly at positions ahead of said nozzle, and said inner tubular member being formed with a series of circumferential openings rearwardly of the inclined front end portion thereof, oppositely arranged air cushioning means on said inner tubular member arranged forwardly of the openings therein, and means for imparting a spiral motion to the air flowing through said inner tubular member, and in the space between said air supply tube and said outer tubular member.
